(57) CLAIM

The ornamental design for a light fixture, as shown and described.

DESCRIPTION

This application is related to commonly owned U.S. design patent applications Ser. No. 29/197,591, filed Jan. 16, 2004 and 29/197,586, filed Jan. 26, 2004 and concurrently filed U.S. design patent applications Ser. No. 29/217,599 and Ser. No. 29/217,590.

FIG. 1 is a perspective view of the light fixture of the present design;

FIG. 2 is a front elevation view thereof, the right side elevation view being a mirror image thereof;

FIG. 3 is a left side elevation view thereof, the rear elevation view being a mirror image thereof;

FIG. 4 is a top plan view thereof; and,

FIG. 5 is a bottom plan view thereof.

The broken lines shown are for illustrative purposes only and form no part of the claimed design.
